UNITED STATES PATENT OFFICE.

GUSTAF DALÉN, OF STOCKHOLM, SWEDEN.

INCANDESCENT-LIGHTING APPARATUS.

1,259,607.

Specification of Letters Patent. Patented Mar. 19, 1918.

Application filed July 6, 1916. Serial No. 107,841.

To all whom it may concern:

Be it known that I, GUSTAF DALÉN, engineer, a subject of the King of Sweden, residing at Skärsätra, Lidingön, Stockholm, Sweden, have invented certain new and useful Improvements in Incandescent-Lighting Apparatus, of which the following is a specification.

The present invention relates to incandescent lighting means and has for object to provide an improved arrangement of incandescent body formed as a disk, cylinder or the like, which is made incandescent or caused to glow by means of a flame in a burner located in front of the incandescent body. Under the influence of the flame such an incandescent body is gradually worn on the spot where the flame strikes the incandescent body, so that a small excavation or hole is formed which acts prejudicially on the escape of the combustion products, as also on the uniform distribution of the light radiating from the incandescent body. When the excavation or hole is sufficiently deep the incandescent body bursts and must be exchanged for another without the mass of the incandescent body having been utilized for generating light on more than one single spot.

These inconveniences are avoided by means of the present invention according to which the incandescent body or its burner is put in motion automatically in such a manner that the wear above mentioned, owing to the influence of the flame on the incandescent body, is distributed almost over the whole surface of the incandescent body. Said motion of the incandescent body or the burner may be imparted by means of mechanism actuated by a diaphragm apparatus in which the admission and escape of gas is controlled by an automatically working valve. Preferably the gas admission to the diaphragm casing of such apparatus is made dependent upon the gas admission to the burner of the incandescent body. The motion of the incandescent body or of the burner may be rectilinear in some cases.

The accompanying drawing illustrates a construction of apparatus according to the invention.

Figure 1 shows the apparatus partly in vertical section and partly in elevation.

Fig. 2 is a side view of the apparatus.

1 indicates the gas admission pipe of a 55 burner 2 arranged in front of an incandescent body formed as a disk 3.

The holder 4 of the incandescent body 3 is mounted in a support 6 on a shaft 5 which is caused to rotate intermittently by suitable 60 mechanism actuated by the diaphragm 11 of the diaphragm apparatus 7.

In the construction shown the automatic valve 8 of the diaphragm apparatus controls the conduit 9 for gas escaping from 65 the diaphragm casing 7, said valve having the form of a plate, movable on edges 18, fixed on the diaphragm casing. Gas is admitted to the casing through an inlet conduit 10, said admission being adjusted by 70 means of the screw valve 19.

When the gas pressure on the diaphragm 11 of the diaphragm apparatus overcomes the pressure of the spring 12 on said diaphragm the diaphragm 11 moves upward 75 and carries with it the valve plate 8 by means of the bow 20 fixed on the diaphragm 11 and coöperating with a bow 21 on the valve plate 8, so that the valve 8 opens the gas outlet conduit 9 whereupon the pressure sinks in the diaphragm casing so that the outlet finally is closed by pressure of the spring 12, acting upon the diaphragm 11 and the bow connection 20, 21 between said diaphragm and the valve plate 8. From the 80 valve 8 projects for the purpose of operating the incandescent body a rod 13 which is fixed on the diaphragm 11 and at its upper end carries a pawl 15 that engages a ratchet wheel 16 on the shaft 5. 17 is a 90 retaining or counter pawl.

Corresponding to the movement of the diaphragm 11 the ratchet wheel 16 is driven step by step and thereby imparts to the holder 4 of the incandescent body and the 95 incandescent body 3 a step by step rotary movement so that the flame of the burner 2 constantly plays upon fresh parts of said incandescent body whereby the disadvantages hereinbefore referred to are obviated. 100

By connecting the admission pipe 10 with the burner conduit 1, as indicated in dotted lines, the additional advantage is gained, that the operation of the diaphragm apparatus 7 is made dependent upon the flame 105 of the burner 2 so that the diaphragm apparatus is put in motion when gas is admitted to the conduit 1 through the cock 22

for lighting the flame, and is put out of operation when the gas is shut off from the conduit 1 for extinguishing the flame. In such an arrangement the flame, when lighted, will begin to act upon the incandescent body 3 on the same place as that on which it finished its action on the incandescent body when the flame was extinguished, whereby a more uniform wear of the incandescent body is effected.

In order to utilize the largest possible portion of the mass of the incandescent body the flame should of course act upon the incandescent body, when in form of a disk, between the center of the incandescent body and its periphery.

While I have herein described a preferred embodiment of my invention it is understood that in practising my invention I do not limit myself to this form but may make such changes in the mechanism for moving the incandescent body and in the movement and shape of the incandescent body as may seem desirable providing that the same fall within the scope of the invention as defined in the appended claims.

Having now particularly described and ascertained the nature of my said invention and in what manner the same is to be performed I declare that what I claim is:

1. In incandescent lighting apparatus, an incandescent body, a burner the flame of which is adapted to render said body incandescent, and means controlled by the flow of gas for presenting different parts of the incandescent body to the action of the burner during lighting.

2. In incandescent lighting apparatus an incandescent body, a burner the flame of which is adapted to render said body incandescent, and means controlled by the flow

of gas for rotating said body during lighting.

3. In incandescent lighting apparatus an incandescent body, a burner the flame of which is adapted to render said body incandescent, an automatic gas operated dia-phragm apparatus, and a connection between one of the movable parts of the dia-phragm apparatus and said incandescent body.

4. In incandescent lighting apparatus an incandescent body, a burner, the flame of which is adapted to render said body incandescent, an automatic gas operated apparatus, a connection between one of the movable members of said apparatus and the incandescent body, and a gas supply to said apparatus connected with the gas supply to the burner.

5. In incandescent lighting apparatus an incandescent body, and means automatically rotating said body under the control of the gas flow during lighting.

6. In incandescent lighting apparatus an incandescent body, and means automatically and intermittently rotating said body during lighting under the control of the gas flow.

7. In incandescent lighting apparatus, an incandescent body, a burner, the flame of which is adapted to render said body incandescent, and means, controlled by the flow of gas, comprising an automatic gas operated apparatus, for rotating the incandescent body during lighting.

In testimony whereof I have affixed my signature in presence of two witnesses.

GUSTAF DALEN.
